US00D502469S

(12) **United States Design Patent** (10) Patent No.: **US D502,469 S**
(45) Date of Patent: **** Mar. 1, 2005**

(54) **COMPACT DISC CARD**

(76) Inventor: **Gerald A. Pierson**, 9931 Rivercrest Ct., Orlando, FL (US) 32825

(**) Term: **14 Years**

(21) Appl. No.: **29/129,283**

(22) Filed: **May 1, 2000**

Related U.S. Application Data

(63) Continuation of application No. 09/292,285, filed on Apr. 15, 1999, now Pat. No. 6,078,557, which is a continuation of application No. 08/856,915, filed on May 15, 1997, now Pat. No. 5,982,736.

(51) **LOC (7) Cl.** **14-02**

(52) **U.S. Cl.** **D14/478**

(58) **Field of Search** **D14/474, 478-80; D19/9, 10; 360/133, 135, 97.01-99.12; 395/186; 369/272-3, 282-8, 291**

(57) **CLAIM**

The ornamental design for a compact disc card, as shown and described.

DESCRIPTION

FIG. 1 is a bottom perspective view of a compact disc card showing the design of my invention;

FIG. 2 is a bottom plan view of FIG. 1;

FIG. 3 is a top plan view of FIG. 1;

FIG. 4 is a front elevational view of FIG. 1, the rear elevational view being a mirror image thereof; and,

FIG. 5 is a left side elevational view of FIG. 1, the right side elevational view being a mirror image thereof.

The broken line drawing of the image shown in FIG. 3 is for illustrative purposes only and forms no part of the claimed design.

1 Claim, 1 Drawing Sheet
